UNITED STATES PATENT OFFICE.

ALEXANDER EIG, OF NEW YORK, N. Y.

APPARATUS FOR SEWING-MACHINE CONSTRUCTIONS.

1,351,029.

Specification of Letters Patent. Patented Aug. 31, 1920.

Application filed April 3, 1919. Serial No. 287,120.

To all whom it may concern:

Be it known that I, ALEXANDER EIG, a citizen of the United States, and resident of the city of New York, in the county of Bronx and State of New York, have invented new and useful Improvements in Apparatus for Sewing-Machine Constructions, of which the following is a specification.

This invention relates to new and useful 10 apparatus for use in connection with sewing-machine constructions, and more particularly concerns sewing-machine constructions of the kind designed for use in shops, factories and like places where the sewing 15 of materials is usually conducted on a large scale.

The principal objects of my invention are: (1) to provide an apparatus of the character specified, having such an arrangement of co- 20 operating devices and parts as will enable the operator to run the sewing-machine at full capacity throughout the working hours, and so to obtain a large increase in production; (2) to provide a novel apparatus having both a labor saving and a safety character, designed to increase production with a decrease of physical effort and mental strain on the part of the operator, and to safeguard inexperienced and careless operators 25 from coming into contact with the operating sewing-machine needle; and (3) to provide as important features of the apparatus: novel carriers, designed to convey the material and to hold it while being sewed, and 30 adapted to be employed either individually or in trains; an automatically operated thread-cutting mechanism; means for disconnecting the train connected carriers; and, finally, mechanism whereby to return the 35 carriers to a convenient place where they may be used over again.

With the foregoing objects in view and others, which will become apparent as the description is proceeded with, the invention 40 resides in the details of construction and in the arrangement and combination of parts hereinafter described, and more particularly pointed out in the claims hereunto annexed.

The preferred embodiment of my invention, as reduced to practice, is illustrated in the accompanying drawings, forming a material part of this specification, and in which:—

Figure 1 is a top plan view of an apparatus constructed in accordance with my invention.

Figs. 2 and 3 are views in front and rear elevation, respectively.

Fig. 4 is a detail view of the device associated with the pressure bar of the sewing- 60 machine for cutting the thread.

Fig. 5 is a view in perspective of a self-balancing transfer device which works on the crank shaft.

Fig. 6 is a view in edge elevation of a type 65 of pressure roller, and of the means for supporting the same above the guideway.

Fig. 7 is a detail, partial sectional view, showing the clutch mechanism for controlling the operation of the crank shaft. 70

Fig. 8 is a detail view of the key in the clutch mechanism.

Figs. 9 and 10 are perspective views, showing, respectively, the top and bottom members of a carrier for the material to be sewed. 75

Fig. 11 is a similar view, showing how two carriers may be coupled together, one of the same being fractionally shown.

Fig. 12 is a detail view in side elevation with the crank shaft in section, showing the 80 mechanism employed for swinging aside a pressure roller.

Fig. 13 is a similar view, illustrating how the swinging lever for the clutch mechanism is operated. 85

Fig. 14 is a detail view of the swinging lever.

Referring more particularly to the accompanying drawings, the numeral 20 denotes a longitudinal work-table, herein shown as 90 centrally supported upon transversely connected standards as 21. Secured upon the work-table, transversely thereof, immediately over the standards, is a sewing-machine construction 22, which may be of any 95 suitable well-known type. Through the usual transmission, the sewing-machine is driven from the electric motor 23, controlled through the medium of a treadle 24 or other suitable means. 100

The specific position of the sewing-machine upon the work-table is such: that its vertically-operating needle 25 works in a path that falls slightly behind a guideway 26, provided longitudinally in the work-table, the machine surface plate 26' being counter sunk to lie flush with the bottom of said guideway; that its corrugated fabric feeding plate 27 will oscillate in the bottom of said guideway, lengthwise thereof; and that its spring-pressed pressure foot bar 28 may be utilized to operatively control a com- 105 110

5 bined pressure roller and thread-cutting structure. Instead of the usual pressure foot, the bar 28 is herein fitted with a block 30 (Fig. 4). Secured to and projecting rearwardly from this block is an angular element 31, to the vertical arm of which is pivotally connected at 32 the movable blade 33 of the thread-cutting scissors 34, so held upon the machine plate 26' as to open toward and just behind the guideway 26. 10 Made fast with the angular element directly below the block 30, is a yoke 35, carrying a roller 36 having end flanges 37 adapted to straddle the guideway.

15 As a means of conveying the material to be sewed and of securely holding the same while being sewed, I provide novel longitudinal fabric carriers, consisting of top members 37 (Fig. 9) and bottom members 20 38 (Fig. 10), having their confronting faces 39 and 40, respectively, longitudinally ridged as shown or otherwise corrugated to provide gripping surfaces between which the material to be sewed may be firmly held. 25 Each top member 37 has its opposite ends rounded as at 41, for a reason to be presently explained; and these ends are slotted as at 42 to receive the upstanding pegs 43 of the bottom member 38, whereby the top 30 is held in proper position with respect to the bottom. The opposite ends of each bottom member extend beyond its top member, and have cut therein transverse kerfs 44, to provide transverse tongues 45; it being observed 35 that at the forward end of the bottom the kerf is cut in the top surface, while at the rear end thereof it is cut in the underneath surface, so that the bottom members may be readily coupled up in an obvious 40 manner in train arrangement.

45 The fabric carriers, thus constructed of two readily separable members and thus capable of being train connected, are of such size, in respect to their width as to fit slidably in the guideway 26. In respect to 50 length, they may vary as may be necessary to accommodate different lengths of fabrics, which, in order to be sewed, must be stretched between the pegs 43 of the bottom member and there clamped tightly by the top member, with the edge or edges to be sewed sliding on the work-table at the rear side of the guideway in position to be carried forward under the vertically-operating 55 needle, which accomplishes the sewing in the usual way. It should be noted here that the provision of the slot and peg structures 41 and 43, respectively, not only permits the fabric carriers to be readily connected and 60 disconnected, but also permits the holding with equal facility of fabrics or materials widely varying in thickness or texture.

65 For a purpose to be presently explained, there rises from each top member 37, midway its width, a longitudinal fin 46 having

70 a gently curved forward end 47 and an abruptly curved rear end 48. So that the oscillating feeding plate 27 of the sewing machine may have a suitable surface to act on for the advancement of the fabric carriers through the guideway, there is secured to the under side of each bottom member 38 a plate 49, made of leather or other suitable frictional material, of a size to cover the entire underneath surface except the end 75 coupling regions as shown (Figs. 10 and 11). When, in the present embodiment, the fabric carriers are initially placed in the guideway, they must be moved along manually until the said oscillating feeding plate 80 27 engages the first one, after which they are drawn along automatically. As the train advances, the carrier on which the plate 27 acts, pushes along those preceding it and pulls along those following it.

85 To further the carrying out of these operations and at the same time to secure the holding of the fabric between the top and bottom members 37 and 38 against shifting or displacement, I provide roller devices, 90 supported to overhang the guideway and in position to exert pressure upon the top member 37.

95 Thus, located over and along that portion of the guideway which constitutes the approach to the machine needle 25, are rollers as 50, each formed with outer rims 51 (Fig. 6) adapted loosely to overlie the opposite sides of the top member 37, and with inner rims 52, the peripheries of which bear upon 100 said top member, but which are spaced sufficiently to allow the free passage of the fins 46 thereof. Each of these rollers is operatively held by a yoke 53, the square stem 54 of which works through suitable 105 openings in the horizontal arms of the channel-shaped bracket 55; the downward movement of said yoke being limited by a key 56, while its upward movement is resisted by a spring 57. Holding each bracket 55 at 110 the proper elevation is a support 58, angular in form as shown, so as to rise from the work-table such a distance from the rear side of the guideway as to allow an intervening space for the free advancement of the fabric 115 edges to be sewed.

120 When the fabric carrier passes the operating needle 25, its top member 37 is acted on by the roller 36, hereinbefore described; and this roller, as it runs down each rounded end 41 of the top member 37, causes the movable blade of the scissors to descend, severing the thread which is carried by the operating needle 25 from the fabric held in one carrier to that held in the next succeeding one. The movable blade of the scissors, urged by a spring 59, rises upwardly again for the next operation, when the roller 36 ascends the adjacent end 41 of the next carrier.

Moving onward from the roller 36, the fabric carrier is first engaged by a roller 60 and then by a roller 61 (Figs. 1 and 2). As the fabric has now been sewed and also re-
 5 moved a distance from the operating needle 25, I here make provision first to allow the removal of the fabric from its carrier, and then to transfer the carrier to other rollers as 62, operatively supported on posts as 63, 70
 10 rising from the work-table at the rear of the guideway. With these ends in view, rollers 60 and 61 are associated with mechanism whereby bodily to swing them clear of the carrier, and also of the path it describes 75
 15 when transferred to the rear rollers 62.

The mechanism associated with these two rollers being precisely alike, a description of that for one of them will suffice for both. In Fig. 12, it will be seen that the roller 60 20 is operatively held by a yoke 64, spring-pressed from the head 65, in which the stem of the yoke has longitudinal movement; the said head 65 being formed on the end of the forwardly curved arm 66, rigid with a shaft 25 67, appropriately journaled in blocks 68, which rise from the work-table. Fast on the shaft 67 is a gear 69 meshed with the toothed segment 70 cut on the follower 71, having movement on a shaft 72, secured in said 30 blocks 68. The rear end of this follower is formed with opposed laterally extending parts 73, between which works a disk 74, eccentrically engaged on the shaft 75. This arrangement is such that when the disk is 35 in the position shown in full lines, the roller 60 will be held in position to engage a fabric carrier; but when the disk is turned into the position shown in broken lines, the roller will be swung in an obvious manner into 40 the rear horizontal position, indicated in broken lines.

As best seen in Fig. 1, there are combined with shaft 75, two double cranks 76 and 77, which turn in the openings 78 and 79, respectively, provided through the work-table. On each double crank is loosely journaled, at its head end, a transfer carrier 80, made in the form shown in Fig. 5, and having provided in its head end between the opposed 50 sides 81 a hollow or bight 82 to receive the fabric carrier; so that, when the cranks are turned, the transfer carriers will pick up a fabric carrier from the guideway, uncouple it from its next following carrier, transfer 55 it over the rollers 60 and 61, and finally deposit it on the rear rollers 62. The lower end of each transfer carrier is enlarged and weighted as at 83, so as to constantly maintain itself in vertical position.
 60 Adjacent the double crank 76, there is loosely mounted on the shaft 75 a gear 84, which revolves in an opening 85, and which is in mesh with a worm gear 85', on the transverse shaft 86, held by bearing hangers 65 underneath the work-table. This shaft 86

has a pulley 87, connected by a belt 88 with pulley 89 on the shaft 90, having support above the work-table in suitable bearing blocks, and having driving connection with one of the rear rollers 62. Said shaft 90 70 also has a pulley 91, driven from the sewing-machine pulley 92 by a belt 93; whereby all of these mechanisms are driven from the sewing-machine in an obvious manner. With the roller 62, to which the shaft 90 is 75 connected, there is engaged an endless traveler 94 which turns upon other similar rollers 95, so that each fabric carrier, upon being deposited on the rollers 62, will be engaged at once by the endless carrier 94 80 and transported back to the end 96 of the work-table.

That the shaft 75 may be revolved only when a fabric carrier has been advanced into position to be picked up by the transfer carriers, I provide a suitable clutch mechanism, herein consisting (Fig. 7) of the spaced collars 97 and 98, both fast on the shaft 75. Partly cut in these collars and partly cut in this shaft is a key-way 99, 90 which extends also into the loose gear 84. Seated in this key-way is a key 100, normally urged forward by a push spring 101 to connect the gear 84 with the shaft. Along its underneath edge, the key 100 is recessed 95 to provide a shoulder 102 in position to be engaged by the narrowed end 103 of the shipping lever 104, when said shipping lever, fulcrumed at 105 and urged by a pull spring 106, is permitted to assume the position shown in full lines in Fig. 13, in which the gear 84 is free to move while shaft 75 is held locked. But when the shipping lever is tripped by a carrier fin 46, as illustrated in broken lines, the key 100, being released, 100 springs forward in the key-way to lock the gear 84 on the shaft. Each time, therefore, the shipping lever is tripped by the front end 47 of a carrier fin, the clutch will be actuated to operate the shaft 75. In general, 110 the fin is located on the carrier close to the rear end thereof, and the shipping lever is located in advance of the first double crank 76, but the precise relative positions of these parts must, of course, be such that when the carrier has advanced far enough in the guideway to be transferred, the double cranks 76 and 77 will be rising 115 through the guideway to effect the transfer.

The relation of the operation of the mechanisms which control the swinging of the pulleys 60 and 61 must be such with respect to the rising of the double cranks through the guideway that these pulleys will be drawn out of engagement with an advancing carrier just a little before the double cranks rise to pick up the carrier. The purpose of this is not only to clear the path for the transfer of the carrier, but also to allow an interval of time for the withdrawal of the 120 125 130

sewed material from between the carrier top and bottom members. Immediately in front of the rollers 60 and 61, the table is cut away closely to the guideway as at 107, so that the 5 sewed material, when it reaches this region, will drop almost directly from the carrier to the floor and by its own weight be drawn from between the top and bottom carrier members as soon as the rollers 60 and 61 are 10 moved from engagement with the top of the carrier. Where the material is not heavy enough to cause its own withdrawal, the operator can readily withdraw the same with a sudden pull as soon as the carrier top is released.

While I have herein illustrated and described the preferred form of my invention, it will be understood that changes and alterations in the details of construction and in 20 other particulars may be made, to which changes and alterations the inventor is entitled, provided the same are effected within the scope of what is claimed.

Having thus described my invention, what 25 I claim and desire to secure by Letters Patent is:—

1. In an apparatus of the kind described, the combination of a sewing-machine having a needle, a longitudinal guideway located at 30 one side of the path of the needle, a longitudinal fabric carrier traveling in said guideway to draw material to be sewed across the path of said needle whereat the sewing operation is accomplished, and mechanism 35 for automatically removing the fabric carrier from said guideway.

2. In an apparatus of the kind described, the combination with a sewing-machine having a needle, longitudinal train connected 40 carriers adapted individually to hold materials to be sewed, provisions for mechanically conducting the train connected carriers past said needle whereat the materials are sewed, means for separating said connected carriers, 45 and mechanism for returning the individual carriers to a convenient place for subsequent operations.

3. In an apparatus of the kind described, the combination with a sewing-machine having a needle, a longitudinal guideway extending past the path of the needle, a longitudinal carrier slidable in the guideway and consisting of top and bottom members between which material to be sewed may be 55 held, means for imparting continuous travel to said carrier to draw the material to be sewed across the path of the needle, and means for yieldingly exerting pressure upon the top member of the carrier whereby the 60 material is held against shifting or displacement.

4. In an apparatus of the kind described, the combination with a sewing-machine having a needle and a yielding pressure bar, of a

longitudinal guideway extending by the 65 needle at one side of the path thereof and below the pressure bar, a longitudinal carrier traveling in the guideway and consisting of top and bottom members between which material to be sewed may be held so as to be 70 drawn across the path of the needle whereat the sewing operation is accomplished, a roller depending from the pressure bar to bear on said top member for holding the material against displacement, and mechanism 75 associated with the pressure bar by which to sever the thread when the sewing is completed.

5. In an apparatus of the kind described, the combination of a longitudinal work-table 80 having a guideway extending lengthwise thereof, a sewing-machine disposed transversely of the work-table and having a needle working at one side of said guideway, a fabric carrier traveling in the guideway 85 and adapted to draw the fabric held thereby across the path of the needle whereat the fabric is sewed, and mechanism for removing the carrier from the guideway.

6. In an apparatus of the kind described, 90 the combination of a work-table having a guideway therein, a sewing-machine disposed on said table and having a needle working at one side of said guideway and a feeding plate oscillating in said guideway, a 95 longitudinal carrier slidable in the guideway and adapted to draw material to be sewed across the path of the needle, said carrier having on its under surface means on which the oscillating feeding plate may act to cause 100 the travel of the carrier through the guideway, and yielding means for exerting pressure on the top of the carrier.

7. In an apparatus of the kind described, the combination with a work-table having a guideway therein, a sewing-machine disposed on said table and provided with a needle working at one side of said guideway and a feeding plate oscillating in said guideway, train coupled fabric carriers slidable in 110 the guideway and adapted each carrier to draw material to be sewed across the path of the needle, said carriers having on their under surfaces means on which the oscillating plate may act to cause the travel of the carriers through the guideway, means for uncoupling the carriers when the sewing is 115 completed, and mechanism removing the individual carriers from the guideway.

8. In an apparatus of the kind described, 120 the combination with a longitudinal work-table having a guideway extending lengthwise thereof, a sewing-machine disposed transversely of the table and provided with a needle working at one side of the guideway and with a feeding plate oscillating therein, train coupled carriers slidable in the guideway and consisting each of top and 125

- bottom members between which material to be sewed may be held, said carriers having on their under surfaces means on which the oscillating plate may act to cause the 65
- 5 travel of the carriers through the guideway, each carrier as it advances drawing its material across the path of the needle whereat the sewing is effected, means yieldingly bearing on the top members of the carriers
- 10 to prevent the displacement of the material, mechanism for automatically severing the threads between the materials held by successive carriers, automatically operated mechanism for uncoupling the carriers and
- 15 removing them individually from the guideway, and mechanism for automatically returning the individual carriers to a convenient place for the next operation.
9. In an apparatus of the kind described, 20 the combination with a work-table provided with a guideway, of a sewing-machine on the work-table having its needle working at one side of the guideway and its feeding plate oscillating in the guideway and its
- 25 pressure bar depending above the guideway, train coupled carriers slidable in the guideway and adapted to be advanced therethrough by the oscillation of said feeding plate, said carriers being adapted each to
- 30 draw materials across the path of the needle whereat to be sewed and being formed each with rounded top ends, a roller attached to the pressure bar to follow the tops of the advancing carriers including the
- 35 rounded ends, thread-cutting mechanism associated with said roller structure and actuated thereby to sever the sewing thread whenever the roller descends a rounded end, mechanism normally inactive for uncoupling and removing the carriers from the 40 guideway, and means coöperating with the last-named mechanism and adapted to be actuated by engagement at a certain point with each advancing carrier whereby to render said last-named mechanism active.
10. In an apparatus of the kind described, 45 the combination with a work-table provided with a guideway, of a sewing-machine on the work-table having its needle working at one side of the guideway and its feeding plate oscillating in the guideway, train coupled carriers slidable in the guideway and adapted to be advanced automatically therethrough when acted on by said oscillating feeding plate, each of said carriers being adapted to draw material to be sewed across the path of said needle, an endless traveler supported on the table in relation to said guideway, means for driving said 50 endless traveler from the sewing machine, mechanism normally inactive for uncoupling the carriers as they advance and for transferring them individually to said endless traveler, and means co-acting with the
- last-named mechanism arranged to be engaged by each advancing carrier and to be thereby actuated whereby to render said last-named mechanism active.
11. In combination, a power driven sewing-machine having a needle, longitudinal mechanical parts for holding and carrying material to be sewed, provisions for mechanically guiding and conducting said parts to go by said needle whereat the material is sewed, an endless traveler driven by the 70 sewing-machine, and mechanism operated from the sewing-machine for receiving said mechanical parts and transferring them to said endless traveler after the material has been sewed.
12. In combination with a sewing-machine having a working needle and an oscillating feeding plate, a longitudinal fabric carrier and means for guiding it onto said oscillating feeding plate in a course to go 80 by said needle, said carrier having on its under surface means on which said oscillating plate may act whereby automatically to effect the advance of the carrier beyond the needle, said carrier consisting of top 85 and bottom members between which material to be sewed may be held in position to be drawn across the path of the working needle whereat the material is sewed, and means associated with the sewing-machine to 90 exert yielding pressure on said top member by which to hold the material against displacement while being sewed.
13. In an apparatus of the kind described, 95 the combination with a work-table provided with a guideway, and with spaced longitudinal openings communicating therewith at right-angles, of a longitudinal fabric carrier traveling in said guideway, mechanism for removing said carrier from the guideway 100 and comprising a shaft traversing said openings and provided with cranks adapted to turn through said openings, self-balancing devices on said cranks and provided with head ends channeled to correspond substantially with said guideway and adapted to embrace the advancing carrier under the upward stroke of the cranks, means for turning said shaft in relation to the travel 105 of the carrier, and means on which the carrier may be deposited under the downward stroke of the cranks.
14. In an apparatus of the kind described, 110 the combination of a work-table having a guide-way and spaced longitudinal openings communicating therewith at right-angles, of a fabric carrier and means for causing it to travel in the guide-way, said carrier being provided with a fin, a structure opposite said guideway and in relation 115 to said openings to receive said carrier, mechanism for transferring said carrier to said structure and comprising a shaft hav-

ing cranks adapted to turn in said openings, self-balancing devices on said cranks adapted to receive said carrier, means for driving said shaft, mechanism normally preventing service application of said driving means and arranged to be engaged and actuated by the fin on the advancing carrier whereby to operate said last-named mechanism to allow a service application of the driving 10 means.

15. In an apparatus of the kind described, a work-table having a guideway and spaced openings communicating therewith, a fabric carrier consisting of top and bottom members traveling in said guideway, said top member having a fin, bodily movable pressure rollers supported to exert yielding pressure on said top member, a structure opposite said guideway and in relation to said 20 spaced openings to receive the carrier, mechanism for transferring the carrier onto said structure and comprising a shaft having cranks working in said openings, self-balancing devices on the cranks for receiving 25 the carrier, mechanism normally inactive for turning the shaft and including a co-acting part positioned to be engaged and actuated by the fin on the advancing carrier whereby to render said mechanism active, 30 and means associated with the shaft by which to swing said pressure rollers clear of said carrier as the self-balancing devices

move to transfer the carrier to said receiving structure.

16. In an apparatus of the kind described, 35 a work-table having a guide-way and spaced longitudinal openings communicating therewith at right-angles, train coupled fabric carriers traveling in said guideway and provided each with a fin, a structure opposite said guideway and in relation to said openings for receiving said carriers, bodily movable pressure rollers supported to exert yielding pressure on the tops of said carriers, mechanism for uncoupling said connected carriers and for transferring them individually to said structure and comprising a shaft having cranks adapted to work in said openings, self-balancing devices on the cranks to embrace and uncouple a carrier under the upward stroke of the cranks, means driving said shaft, mechanism controlled by the shaft for moving said pressure rollers clear of the carriers, mechanism normally preventing service application of 45 said driving means, and means co-acting with the last-named mechanism and positioned to be engaged and actuated by the fin on each advancing carrier whereby to operate said last-named mechanism to allow a 50 service application of the driving means.

In testimony whereof I have signed my name to this specification.

ALEXANDER EIG.
